UNITED STATES PATENT OFFICE.

EDWARD A. TOMLIN, OF BONNER SPRINGS, KANSAS.

FASTENING DEVICE FOR ANTI-SKID-CHAINS.

1,344,778.

Specification of Letters Patent. Patented June 29, 1920.

Application filed January 27, 1920. Serial No. 354,374.

To all whom it may concern:

Be it known that I, EDWARD A. TOMLIN, a citizen of the United States, and resident of Bonner Springs, county of Wyandotte, and 5 State of Kansas, have invented a certain new and useful Improvement in Fastening Devices for Antiskid-Chains, of which the following is a complete specification.

The present invention relates to anti-skid 10 chains for vehicle wheels, and aims to provide an improved form of fastening device for securing such chains in position when applied to the wheels.

Accordingly I have devised an improved 15 fastening device for detachably securing together the ends of the side strands of the anti-skid chain, and the form of said device is such as to facilitate the connecting operation as well as the disengagement of the 20 same from the chain when the latter is to be removed from the wheel.

It is also sought to provide a fastening means which will not only be convenient in 25 its operation, but which will also enable the chain to be applied with a somewhat greater degree of snugness to the wheel.

With these objects in view the invention will now be described with reference to the accompanying drawing illustrating a form 30 of embodiment of the improvement, after which the features therein deemed to be novel will be particularly set forth and claimed.

In the drawing—

35 Figure 1 is a perspective view of one of the fastening devices, shown in attached relation to the end portion of one of the side strands of an anti-skid chain;

Fig. 2 is a side view of the same; and

40 Fig. 3 is a plan view, on a smaller scale, showing the end portions of both side strands of the chain connected together by a pair of the improved fastening devices.

Referring to the said drawing in detail, 45 this illustrates the device as comprising a main or longitudinal portion 4 formed at one end with a hook 5 adapted to be permanently connected with one of the terminal links 6 of one of the side strands 7 of the

50 anti-skid chain. At its other end the device is formed with a slightly bowed and outward turned (that is, turned outwardly with reference to the position of the device when the chain is applied to a wheel) finger portion 8 adapted for engagement with the other terminal link 9 of the corresponding side

strand 7, as illustrated in Fig. 3. The finger 8 is forked and provided with a pivot pin 10 for pivotally mounting a keeper or closure element 12, which is of approximately the 60 same length as the main or longitudinal portion 4 of the device. The middle portion 13 of the closure element 12 is somewhat enlarged and provided with a suitable opening 14 for fitting over the end of a post 65 15 which is rigid with the middle portion of the main body 4 of the device and projects outwardly therefrom. The post 15 is formed with a shoulder 16 adapted to limit the closing movement of the element 13 to a 70 position approximately parallel with the main body portion 4 of the fastener. In this position said closure element is retained by means of a spring cotter 17 inserted through an opening 18 in the outer end of the post 75 15. Preferably the free end of the closure element 12 is of tapered form, for facilitating its insertion through the link 9 in the connecting operation.

It will thus be apparent that I have provided a simple as well as inexpensive device 80 adapted to afford greater convenience in the application or removal of chains of the character described. The free tapered end of the closure element 13 provides a handle 85 whereby the same may be conveniently taken hold of and manipulated and readily inserted within the corresponding chain link 9 whenever the links 6 and 9 are to be connected. This structure also enables a suitable leverage action to be exerted for drawing up the terminals of the side strand 7 so 90 that a more snugly fitting chain may be employed if desired, and the link 9 may obviously be readily drawn by the swinging 95 movement of the element 13 into the concaved side of the finger 8, after which the element 13 is latched in closed position by the spring cotter 17. The parts are securely retained in this position until the chain is to 100 be removed, when the free projecting end of the closure element 13 again forms a convenient finger engaging portion for operating the device and disconnecting the chain terminals.

Having described the invention, what I claim is:

1. A fastening device for detachably connecting anti-skid chain terminals, comprising a main longitudinal portion secured to 110 one of said terminals and having an outwardly projecting finger for detachably en-

gaging the other of said terminals, a rigid post spaced from said finger and projecting outward from said main longitudinal portion, a closure element pivoted to the outer 5 end of said finger and provided with an opening intermediate its ends for fitting over the outer end of said post, and a cotter pin fitted removably in the outer end of said post for retaining said closure element in 10 closed position, the free end of said closure element projecting in position for finger-engaging purposes.

2. A fastening device for detachably connecting anti-skid chain terminals, comprising

ing a main longitudinal portion secured to 15 one of said terminals and having an outwardly projecting finger for detachably engaging the other of said terminals, a rigid post spaced from said finger and projecting outward from said main longitudinal portion, and a closure element pivoted to the outer end of said finger and having its middle portion adapted for latching engagement with said post and its free end portion tapered and extending in position for 25 finger-engaging purposes.

In witness whereof I affix my signature.

EDWARD A. TOMLIN.
